UNITED STATES PATENT OFFICE.

HOWARD D. COLMAN, OF ROCKFORD, ILLINOIS, ASSIGNOR TO BARBER-COLMAN COMPANY, OF ROCKFORD, ILLINOIS, A CORPORATION OF ILLINOIS.

KNOTTER.

1,348,929.

Specification of Letters Patent. Patented Aug. 10, 1920.

Application filed October 26, 1918. Serial No. 259,766.

To all whom it may concern:

Be it known that I, HOWARD D. COLMAN, a citizen of the United States, residing at Rockford, in the county of Winnebago and 5 State of Illinois, have invented certain new and useful Improvements in Knotters, of which the following is a specification.

The object of this invention is to eliminate the shearing function of the tying bill and 10 to provide special means for shearing the strand or strands clamped in the bill.

I have herein shown my invention as embodied in a weaver's knotter of the type disclosed in Patent No. 1,241,758, granted 15 Oct. 2, 1917, upon an application filed by Earle D. Parker.

In the accompanying drawings, Figure 1 is a fragmental side elevation of one form 20 of knot-tying implement embodying my invention and illustrating the manner in which it is used. The parts are shown in the initial position. Fig. 2 is a plan view showing the parts in the positions occupied when the tying bill has completed somewhat more 25 than one revolution. Fig. 3 is a diagrammatic view of the tying bill and shear. Fig. 4 is a fragmental perspective view showing the parts in approximately the positions occupied in Fig. 2. Fig. 5 is a fragmental 30 plan view showing how the threads are placed in operative relation to the implement, and representing the parts in the initial position.

The invention is herein shown as embodied 35 in a mechanism comprising a tying bill for forming the loops of the knot and for clamping one of the threads; a device for shearing said thread; means for tightening the loops of the knot and stripping the knot from 40 the tying bill; a device for shearing the other thread and assisting to strip the knot from the tying bill; and guides for properly positioning the threads with relation to the mechanism.

45 While the invention may be embodied in various forms and used for various purposes, I have herein shown a mechanism which is especially intended for uniting the threads of a bobbin and a spool, and which 50 is arranged to be supported upon the hand of the operative by means similar to that shown in said Parker patent, said means

comprising a handle A⁶. A standard or framework A is rigidly fixed to the handle A⁶ and is provided with bearings for the shaft 55 of the tying bill; said tying bill comprises a relatively rigid jaw C⁵, a spring jaw C⁸ and a clamping jaw C¹⁴ arranged to be pivotally moved into and out of the space between the jaws C⁵ and C⁸ by means of a cam 60 barrel C. On the tying bill shaft is a spiral pinion that meshes with a spiral segment B⁷ (Fig. 1). Said segment is rotatively mounted upon a stud B which is fixed to the handle A⁶. Fixed with relation to the gear segment 65 is a thumb fork B⁵ by means of which the segment may be oscillated to rotate the tying bill in one direction through approximately one and a half revolutions and in the opposite direction to the initial position. 70

The means herein shown for tightening the loops of the knot and stripping the knot from the tying bill comprises a thread-holding arm E pivoted to swing on the axis D. The forward end of said arm is in form of a 75 hook E¹¹ to receive one of the threads to be tied, namely, the thread extending from the bobbin. A torsion spring E³ tends to hold the arm E in its initial position, such position being determined by contact of the 80 arm with a stop A⁸ on the standard A.

A thread-clamping arm D⁶, provided at its forward end with two upwardly-extending clamping fingers D⁷ that lie at opposite sides of the holding arm E, is pivoted at its 85 rear end to one arm of a bell crank D⁴ that swings on the axis D. The other arm of the bell crank is provided with a roller stud that lies in a cam groove B⁸ (Fig. 5) formed in an arcuate flange B⁹, which is fixed with 90 relation to the gear segment B⁷. The shape of the cam groove B⁸ is such as to cause the bell crank D⁴ to swing back and forth in each stroke of the thumb-fork B⁵. During the operating (i. e., downward) stroke of 95 the thumb-fork, the arm D⁶ is advanced so as to cause the fingers D⁷ to clamp the thread lying in the hook E¹¹ of the arm E. As the arm D⁶ advances, a spring latch E⁴ (Fig. 2) on the arm E engages a stud D⁸ on the bell 100 crank D⁴, so that when the movement of the bell crank is reversed the arm E is caused to move with the bell crank and the arm D⁶, in which movement the said arms swing lat-

erally away from the tying bill to tighten the loops and strip the knot off the tying bill. As the thumb fork completes its operative stroke, the spring latch E^4 is disengaged from the pin D^8 by means of a stop pin A^9 .

At the side of the tying bill, opposite to the arms E and D^6 , is a stationary thread guide C^{10} for the thread extending from the bobbin.

The position of the hook E^{11} with reference to the tying bill is such that the tying bill in its revolution cannot engage the portion of the bobbin thread that extends between said hook and bill.

For supporting the thread extending from the spool, suitable means may be provided, as, for example, a bracket 1 (Fig. 4) fixed to a frame member 2, said frame member being rigidly fixed to the standard A. Upon the bracket 1 is a thread clamp 3 which may consist, as herein shown, of a jaw 3^a fixed to said bracket, and a co-acting spring jaw 3^b attached to the bracket, said jaws having flaring forward ends to facilitate the insertion of the thread into the clamp. A pin 4 (Fig. 1) fixed to the jaw 3^a and extending through a perforation in the jaw 3^b limits the extent to which the thread may be inserted into the clamp. The clamp 3 is located forwardly of the tying bill. The bracket 1 is notched to form a guide 5 for the thread extending from the spool. The clamp 3 also may be termed a guide or support for the spool thread.

The waste end of the thread coming from the spool is cut off by a device 6, which is substantially like the device 6 fully disclosed in said patent.

40 The guides 3 and 5 are spaced apart, and the bottom of the notch of the guide 5 is below the horizontal plane of the pin 4, so that the portion of the spool thread extending between the tying bill and the guide 5 is below the portion extending between the tying bill and the guide 3.

Any suitable means may be provided for advancing the device 6 to grasp the strand extending between the tying bill and the guide 5. Herein I have shown said device as fixed upon an arm 12 which may be pivoted to the frame member 2, as shown in said patent. A link 14 connects the forward portion of the arm 12 to a member 15 fixed to the arm D^6 . Thus, when the arms E and D^6 swing outwardly to tighten and strip the knot, the device 6 is advanced to grasp the portion of the spool thread which is to be severed, namely, the portion extending between the knot and the guide 5. The path of the device 6 is close to the tying bill in order that the spool thread shall be severed as close to the knot as possible.

The jaw of the device 6 may be swung to shear, clamp and release the spool thread

by any suitable means, as, for example, that fully disclosed in the above mentioned patent.

The means for shearing or trimming off the waste end of the bobbin thread comprises a spring shear blade 20 fixed to the bracket 1, and a shear blade 21 fixed to a slide 22. Said slide has a dove-tail guide 23 which slides in a correspondingly-shaped groove 24 (Fig. 4) in the standard or frame 75 work A. The slide 22 is further guided by means of a bar 25 fixed to the slide and extending through a guide 26. The blade 21 is provided with a finger 27 having a rounded forward end which is arranged to engage the spring shear blade 20 and guide the latter into operative relation to the blade 21. The slide 22 is reciprocated by means of a lever 28 pivoted at 29 to the framework and having a pin-and-slot connection with 80 the slide. On the lever 28 is a roller stud 30 that lies in the cam groove 31 of a plate 32 fixed to the fork B^5 .

As indicated in Fig. 2, the shear blade 21 reciprocates in the space between the tying 90 bill and the guide C^{10} , and relatively close to the tying bill so as to sever the bobbin thread as close to the knot as possible. The blade 20 is located at one side of the orbit of the bill. The path of reciprocation of the 95 blade 21 intersects said orbit.

Assuming the implement to be mounted upon the left hand of a spooler tender and the mechanism to be in initial position (i. e., in the position shown in Figs. 1 and 5), the 100 threads are manipulated as follows:

When it is desired to unite the end of the thread upon a bobbin to the end of the thread upon a spool, the operative lays the end of the bobbin thread across the palm of the 105 right hand, the loose end projecting beyond the thumb, and the hand being held palm up. The rotation of the spool is then stopped by placing the left hand on the top of the spool, and the end of the spool thread 110 found and placed in the palm of the right hand, the loose end projecting slightly beyond the little finger. The right hand, being still held palm side up, is raised and the spool thread placed in the clamp 3. The right hand is then turned toward the left to lay the bobbin thread in the hook E^{11} and behind the tying bill and in the guide C^{10} . The right hand is then turned farther toward the left and brought forward, thus carrying the 120 spool thread over the bobbin thread and down into the guide 5. The bobbin thread now extends through the hook E^{11} , behind the tying bill, and into the guide C^{10} , and the spool thread is doubled over the bobbin 125 thread, both strands of the spool thread lying at the same side of the tying bill, namely, at the side toward which the tying bill turns when beginning its revolution. The operative then depresses the thumb 130

fork B⁵ with the thumb of the left hand. As soon as the tying bill and the device 6 have clamped the threads, the operative drops the loose ends, takes hold of the united threads, draws said threads out of the clamp 5 and removes her hand from the spool.

The operation of the mechanism may be briefly described as follows:

Depression of the thumb fork B⁵ causes 10 the tying bill to rotate counter-clockwise, thereby engaging the doubled spool thread and coiling the threads around the bill. After about three-fourths of a revolution, the portion of the bobbin thread which extends between the tying bill and the guide C¹⁰ 15 is received in the open tying bill. During the ensuing half revolution, the bobbin thread is clamped by the tying bill, after which the advancing shear blade 21 coacts 20 with the blade 20 to shear the bobbin thread, and the device 6 is advanced to clamp and shear the portion of the spool thread which extends between the tying bill and the guide 5. The bobbin thread has 25 also been clamped by the fingers D⁷ and hook E¹¹, and the arms E and D⁶ have swung laterally, thus pulling the loops of the knot onto the point of the tying bill. As the arms E and D⁶ and the device 6 30 continue to move laterally, the loops of the knot are pulled off the tying bill and drawn tight, and the thread end finally pulled out of the tying bill. The end clamped in the device 6 is released as said device is moved 35 with the arm E into the initial position by the spring E³. The operative then swings the thumb fork B⁵ up to the initial position, thereby restoring the parts of the mechanism to their initial positions.

40 I claim as my invention:

1. A knot-tying mechanism having, in combination, a rotary tying bill; means for supporting a thread extending across the tying bill, said bill being adapted to clamp 45 said thread; means for supporting a thread which is doubled over the other thread; a shear for severing a portion of said other thread; a shear for severing a portion of said doubled thread; means for revolving 50 the tying bill against the doubled thread, the other thread being thereafter caught by the tying bill and clamped; and means for actuating said shears.

2. A knot-tying mechanism having, in 55 combination, a rotary tying bill; means for supporting a thread extending across the tying bill, said bill being adapted to clamp said thread; two thread guides for supporting a thread which is doubled over the 60 other thread, said guides being spaced apart so as to support the strands of the doubled

thread at an angle to each other; means for shearing one of said strands of the doubled thread; means for shearing the waste end of the other thread; and means for actuating the tying bill and the shearing means. 65

3. A knot-tying mechanism having, in combination, a rotary tying bill; an oscillatory arm adapted to clamp a thread and move away from the tying bill to tighten 70 the knot and strip the thread from the tying bill; means for supporting a thread which is doubled over the other thread; a stationary shear blade adjacent to the tying bill; a coacting reciprocating shear blade 75 for severing said other thread; and means for shearing a portion of said doubled thread.

4. A knot-tying mechanism having, in combination, guides for supporting two 80 threads, one of which threads is doubled over the other, a tying bill for coiling the doubled thread and clamping the other thread, a shear for trimming off one strand of the doubled thread, and a shear operating adjacent to the tying bill for trimming off one strand of said other thread after 85 said strand has been clamped in the tying bill.

5. A knot-tying mechanism having, in 90 combination, a rotary tying bill adapted to clamp a thread, a stationary guide for supporting said thread, a stationary shear blade, and a coacting shear blade arranged to reciprocate in the space between the 95 tying bill and said guide and timed to shear said thread after the latter has been clamped in the bill.

6. A knot-tying mechanism having, in combination, a rotary tying bill adapted to 100 clamp a thread, a stationary guide for supporting said thread, a stationary shear blade, and a coacting shear blade arranged to reciprocate and timed to shear said thread after the latter has been clamped in the 105 bill, said stationary shear blade being located out of the path of said bill and said reciprocating shear blade moving across the path of part of said bill.

7. A knot-tying mechanism having, in 110 combination; a rotary tying bill adapted to clamp a thread, stationary guide means for supporting said thread, and shear means independent of said guide means, said shear means being located between said guide means and said bill and timed to shear said thread after the latter has been clamped in the bill. 115

In testimony whereof, I have hereunto set my hand.

HOWARD D. COLMAN.
